UNITED STATES PATENT OFFICE

JAMES H. CLARKE AND WILLIAM R. CLARKE, OF CLEVELAND, OHIO

SPRINKLER HEAD

Application filed January 19, 1932. Serial No. 587,523.

This invention relating, as indicated, to 5 sprinkler heads has specific reference to the form of construction of an automatic sprinkler head of the type connected to a water supply line and provided with some such means as a fusible link which, under the heat generated by a conflagration, will permit a valve member in such sprinkler head to become unseated and thereby project a stream of water onto such conflagration for the purpose of extinguishing the same.

As is well known to those familiar with the art, a fire of relatively small proportions 15 is capable of generating sufficient heat so that the fusible link will turn on the stream of water. The damage occasioned by such circumstances is usually traceable, in a large measure, to the injury by the water from the 20 sprinkler head and only a small measure is actually due to the fire.

In order to safeguard against an inadvertent closure of the line leading to the sprinkler heads and accordingly, to insure that 25 the sprinkler apparatus, at all times, has available a supply of water, only a central controlling valve, usually at a remote point, is employed for controlling the flow to the sprinkler heads.

In buildings as they are at present constructed this valve for the sprinkler system is usually located at a point not well known to the occupants of the building, so that 30 if a small blaze sets off a sprinkler head, considerable water damage will result before the proper parties can be summoned to turn off the water supply.

It is among the objects of our invention 35 to provide a form of sprinkler head construction in which the normal operation of the head, in the manner well known, is not interfered with. A sprinkler head constructed in accordance with the principles of our invention cannot be inadvertently 40 actuated to render the same ineffective for

the purposes for which it has been designed.

The sprinkler head comprising our invention is provided with means whereby the flow of water released by the melting of the fusible link may be quickly and completely shut off by simply tapping a lateral projection on such head.

It is among the objects of our invention to provide a sprinkler head having all of the above named desirable characteristics. 55 Other objects of our invention will appear as the description proceeds.

To the accomplishment of the foregoing and related ends, said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a part sectional, part side elevational view of a sprinkler head constructed in accordance with the principles of our invention; Fig. 2 is a view similar to Fig. 1 showing the main closure member removed from the head; and Fig. 3 is a view similar 75 to the previous figures illustrating the auxiliary closure member in sealing engagement over the discharge opening.

Referring now more specifically to the drawing and more especially to Fig. 1, the 80 sprinkler head constructed in accordance with our invention is generally of the usual form, in that it is provided with a threaded extension 1 adapted to be screwed into a nipple or similar fitting in a pipe line, so 85 that water or other fluid may be supplied to the passage 2. The lower end of the body 3 of the head is provided with a yoke 4. The yoke 4 may, at its lower end, be provided with the usual deflector for breaking 90

up the stream of water discharged in case of fire.

At the lower end of the passage 2, the head is formed with inner and outer valve seats 5 and 6 respectively. Normally seating on the outer valve seat 6 is a main closure member 7 held in seating engagement on its seat by means of a fusible link 8, which is supported at its opposite end by the yoke 10. The link 8 has been only diagrammatically illustrated and it is to be noted that the form of the means for maintaining the main closure member 7 on its seat may be varied without departing from the principles of this invention.

The main closure member 7 is provided with an axially extending projection 9 which, along with an enlargement 10 in the contiguous wall of the body 3, forms a pocket in which is positioned a spherical auxiliary closure member 11.

The wall of the body member 3 adjacent the pocket containing the member 11 is provided with an outwardly directed bore 12 in which is positioned a reciprocable actuating stem 13. Leakage past the stem 13 is prevented by means of a packing nut 14.

The inner end of the stem 13 is hook-shaped, as at 15, and is engaged in an aperture 16 provided therefor in the member 11, the form of such aperture being most clearly illustrated in Fig. 3. The stem 13 is also provided with an annular flange 16a for the purpose hereinafter more fully explained.

The stem 13 is, at its outer end, provided with a flange 17 which may be removably secured thereto and which serves as an abutment for the compression spring 18 which normally urges the stem 13 axially outwardly. The flange 16a on the stem 13 prevents the spring 18 from withdrawing such stem too far, especially after the ball 11 has been moved into the position indicated in Figure 3.

The function and operation of the above described form of construction is briefly as follows:

The sprinkler head will be installed in the usual manner and the fusible link 8, or similar means provided for that purpose, will maintain the main closure member 7 on its seat 6 until sufficient heat generated by a fire in the vicinity of the head causes such link to melt and thereby permit the main closure member 7 to be unseated and blown out under the influence of the pressure within the passage 2.

When the main closure member 7 is seated, as illustrated in Fig. 1, the projection 9 will trap the ball 11 in the pocket provided therefor, so that such ball cannot be accidentally displaced by movement of the rod 13. After the main closure member 7 has been unseated, the flow of fire extinguishing fluid through the passage 2 is unobstructed. The

hook-shaped terminal 15 of the rod 13 engaging the lip adjacent the aperture 16 is effective to prevent the eddy currents, incidental to the flow of extinguishing fluid, from moving the ball 11 out of its pocket.

After the fire has subsided, the flow of fire extinguishing fluid may be completely shut off by inward axial movement of the rod 13, which may be accomplished by simply tapping the end 17 either with the hand or some suitable tool.

As the rod 13 is moved axially inwardly, the ball 11 is moved onto the edge 19, which may be a part of the valve seat 5. As soon as the center of gravity of the ball passes the vertical line through the edge 19, the ball will roll over onto the seat 5 and assume the position illustrated in Fig. 3. The ball, in rolling over onto its seat, is disengaged from the stem 13, due to the particular formation of the hook 15 and the recess 16.

As soon as the fire has been extinguished, the auxiliary closure member 11 may then be moved over onto its seat by simply tapping the end of the rod 13. The member 11, when seated in the manner described, is effective to completely close off the flow of fire extinguishing fluid, whether liquid or gaseous.

The upper end of the threaded portion 1 may be provided with a peened in projection 20 which is effective to prevent the ball 11 from passing upwardly through the passage 2, thereby preventing the same from going back into the water line or from falling out of the head after the same has been removed.

As above indicated, the auxiliary closure member 11 may not be inadvertently seated to obstruct the flow of fluid until the main closure member 7 has first been unseated. The additional structure to the sprinkler head comprising our invention, therefore, in no way, curtails the possibility of the sprinkler head functioning in the manner for which it has been designed upon the occurrence of a fire.

Other advantages incidental to the employment of the apparatus comprising our invention will be so apparent to those familiar with the art that a further description thereof is believed unnecessary.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. A sprinkler head having a discharge opening, outer and inner valve seats about said opening, outer and inner closure members for such opening respectively adapted

to engage said seats, means associated with said outer member which when such member is seated locks said inner member in unseated position, and means for seating 5 said inner member.

2. A sprinkler head having a discharge opening, outer and inner closure members for such opening, means associated with said outer member which when such member is seated locks said inner member in unseated position, means for maintaining said inner member unseated after said outer member has been unseated, and means for seating said inner member.

15 3. A sprinkler head having a discharge opening, a main closure member for such opening, a spherical auxiliary closure member within said head, an annular valve seat for said auxiliary member around said opening, and means associated with said main closure member which when such member is seated locks said auxiliary member off its seat, and means for moving said auxiliary member on to its seat.

25 4. A sprinkler head having a discharge opening, a main closure member for such opening, a spherical auxiliary closure member within said head, an annular valve seat for said auxiliary member around said opening, and means associated with said main closure member which when such member is seated locks said auxiliary member off its seat, means for locking said auxiliary member off its seat after said main member has 30 become unseated, and means for seating said auxiliary member.

5. A sprinkler head having a discharge opening, a main closure member for such opening, a spherical auxiliary closure member within said head, an annular valve seat for said auxiliary member around said opening, and means associated with said main closure member which when such member is seated locks said auxiliary member off its seat, and means effective to hold said auxiliary member off its seat after said main member has become unseated and movably effective to seat such auxiliary member.

6. A sprinkler head having a discharge opening, a main closure member for such opening, a spherical auxiliary closure member within said head, an annular valve seat for said auxiliary member around said opening, and means associated with said main closure member which when such member is seated locks said auxiliary member off its seat, and means extending out of the body of said head for seating said auxiliary closure member.

60 7. In a sprinkler head provided with a discharge orifice, axially spaced valve seats associated with said orifice, an outer main closure member for said orifice adapted to engage one of said seats, an inner auxiliary spherical closure member for said orifice

adapted to engage the other of said seats, a projection on said main closure member which when such member is seated locks said inner member off its seat, and a rod projecting laterally out of said head terminally 70 engaging said inner member to hold the same off its seat and adapted upon axial movement to seat said inner member.

Signed by us this 16th day of January, 1932.
